UNITED STATES PATENT OFFICE.

HARRY H. HOOP, OF CHICAGO, ILLINOIS, ASSIGNOR TO BUFORD G. LINCOLN, OF CHICAGO, ILLINOIS.

MOP CLEANER.

Application filed December 29, 1920. Serial No. 431,306.

To all whom it may concern:

Be it known that I, HARRY H. Hoop, a citizen of the United States, and a resident of Chicago, in the county of Cook and State of Illinois, have invented certain new and useful Improvements in Mop Cleaners, of which the following is a full, clear, and exact description.

The invention relates to mop-cleaners.

It is now common practice to use fibrous mops which are usually treated with an oil or chemical, to wipe dust from the floor or other places. It is desirable that the dirt and dust accumulated on the mop be removed therefrom and disposed of from time to time without causing the dust to be scattered wherever the cleaning may occur. The primary object of the present invention is to provide an improved cleaner which is adapted to remove the dust and dirt from a mop and to retain the accumulated material without scattering it throughout the place where the cleaning occurs.

A further object of the invention is to provide a cleaner of this character which is simple in construction and can be produced at a comparatively low cost.

The invention consists in the several novel features hereinafter set forth and more particularly defined by claims at the conclusion hereof.

In the drawings: Fig. 1 is a view, partly in section and partly in elevation of a cleaner embodying the invention. Fig. 2 is a section taken on line 2—2 of Fig. 1. Fig. 3 is a section on an enlarged scale through one side of the cleaner.

The invention is exemplified in a structure comprising a base 6, which is adapted to rest on the floor, is formed of sheet metal, and is adapted to form the bottom of a dust-collector chamber 7. The base is hollow to leave a space 8 therebeneath for driving mechanism for the suction-fan, and comprises an integral top-wall 11, a cylindrical side and a flange 6^a of double thickness, as shown. Tubular standards 9 are secured in sockets 10 which are riveted to the top-wall 11 of the base 6 and the upper ends of these standards are connected by a curved portion 12 which serves as a handle whereby the cleaner may be lifted or carried, this construction being one which makes it possible to form the standards and handle of

a single continuous metal tube. A mop-

holder 13 consists of an annular fan-casing or hopper 14, which is adapted to receive and surround the mop, a horizontal flange 15 which is riveted to sockets 16 which are secured to the tubular standards 9 to secure the hopper above the collector chamber 7, and a downturned rim or flange 17 which is provided with a groove 20. The side of the base 6 is provided with a similar groove 21 and these grooves are adapted to receive and hold retaining hoops 22 and 23 on the upper and lower ends of a cylindrical fabric member 24 forming the dust-collecting chamber 7. The hoops 22 and 23 are formed of split spring wire so they can be readily detached from and attached to the base 6 and holder 13 to permit the bag to be disconnected to provide access to the collecting chamber when it is desired to remove the accumulated dust. A suction-fan rotor 25 formed of a stamping and with suitable inclined blades is adapted to rotate in the lower portion of the hopper 14 to suck air through the mop held in the hopper. The rotor 25 is secured to the upper end of a vertical shaft 26 which is carried in a bearing 27 which is secured to the upper end of a conoidal sheet-metal sleeve 28, the lower end of which is flanged and riveted to the top-wall 11 of the base 6, as at 29. Wall 30 is dished downwardly, as at 30, and is provided with a bearing 31 for the lower end of shaft 26. An operating shaft 32 extends through one of the tubular standards 9, is provided with a hand-crank 33 at its upper end; is carried in a bushing 32' which is fixed in the lower end of said standard 9, and has secured to its lower end, by a screw-thread 36, the flanged hub 34 of a sprocket-wheel 35. Sprocket 35 drives a sprocket-chain 37 which operates a small sprocket 38 on the lower end of the fan-shaft 26. Cross-rods 39 are secured in the hopper 14 above the fan-blades and are adapted to support and hold the mop and prevent its fibres from being carried around by the fan blades. By thus holding the fibres of the mop, the blades will act as beaters to supplement the suction of the fan in dislodging dirt and dust from the mop. A suitable clip 40 is secured to the handle 12 so that the handle of the mop may be secured to the cleaner when desired, either when the cleaner is or is not in use.

In operation, the operator will place the

fibres of the mop to be cleaned in the fan-casing or hopper 14 and above the holder-bars 39 and then turn the crank 33, which will operate the shaft 32, sprocket 35, chain 36 and sprocket 37 to drive the shaft 6 and the fan. These fan-blades will beat the fibres of the mop and create a downward current and suction of air to deliver the dust and dirt removed from the mop into the collector-chamber 7, the fabric member 24 permitting the air to escape from the chamber while retaining the dust therein. When it is desired to remove the collected material from the collector-chamber, it is only necessary to release one of the spring-hoops and collapse the member, whereupon the material in the chamber 7 will be accessible for removal.

The invention exemplifies a cleaner which is adapted to remove and collect the dust and dirt from mops without scattering it. The construction is one which may be made at a low cost, the parts being made mainly of sheet metal. The entire cleaner is adapted to be easily carried from place to place and when not in use may be conveniently stored in a corner or closet.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a mop cleaner, the combination of a horizontally disposed fan casing having its upper end open and formed to receive a mop therein, a dust collector chamber below said casing, a horizontally rotating fan mounted in said fan casing for forcing a current of air through the casing to remove the dust from the mop and deposit it in said chamber, and means for driving said fan.

2. In a mop cleaner, the combination of a fan casing adapted to receive a mop therein and provided with bars to hold the mop, a dust collector chamber, a fan rotatably mounted in the fan casing for forcing a current of air through said casing to remove the dust from the mop and deposit it in said chamber, and means for operating said fan.

3. In a mop cleaner, the combination of a fan casing having its upper end open and adapted to receive a mop, a dust collector, a fan in said casing for forcing a current of air to remove the dust from the mop and deposit it in said chamber, means for driving said fan supported with said casing, the entire cleaner being portable, and means whereby it may be carried from place to place.

4. In a mop cleaner, the combination of a horizontally disposed fan casing having its

upper end formed to receive a mop, a dust collector chamber below said casing, a horizontally rotating fan for forcing a current of air through the casing to remove the dust from the mop and deposit it in said chamber, and means for driving said fan, comprising a vertically extending shaft and a driving connection for the shaft below the chamber.

5. In a mop cleaner, the combination of a horizontally disposed fan casing having its upper end formed to receive a mop, a dust collector chamber below said casing, a horizontally rotating fan for forcing a current of air through the casing to remove the dust from the mop and deposit it in said chamber, means above the casing to hold a mop handle, and means for driving said fan.

6. In a mop cleaner, the combination of a fan casing adapted to receive a mop, a base below said casing, a cylindrical fabric member extending between and having its upper and lower ends secured to the casing and the base and forming a dust collecting chamber, a fan rotatably mounted in the casing and adapted to force air from the mop into said chamber, and means for driving said fan.

7. In a mop-cleaner, the combination of a fan-casing adapted to receive a mop, a base, standards securing the base and casing in spaced relation, a fabric member extending between and having its upper and lower ends secured to the casing and base to form a dust collecting chamber in communication with the casing, fan-blades for forcing air through the casing to remove the dust from the mop held therein, and means for operating said fan comprising a shaft supported by the base.

8. In a mop cleaner, the combination of a fan-casing adapted to receive a mop, a base, standards securing the base and casing in spaced relation, means between the casing and base to form a dust collecting chamber in communication with the casing, fan-blades for forcing air through the casing to remove the dust from the mop held therein, a vertical fan-shaft, means for driving said fan-shaft, and a hollow-support secured to the base and provided with a bearing at its upper end for said shaft.

9. A mop-cleaner, the combination of a fan-casing adapted to receive a mop, a hollow base, standards securing the base and causing in spaced relation, means between the casing and base to form a dust collecting chamber in communication with the casing, fan-blades for forcing air through the casing to remove the dust from the mop held therein, a vertical fan-shaft, and means for driving said shaft comprising gearing in said base.

10. In a mop-cleaner, the combination of

9

a fan-casing adapted to receive a mop, a base, standards securing the base and casing in spaced relation, means to enclose the space between the casing and base to form a dust collecting chamber, fan-blades for forcing air through the casing to remove the dust from the mop and deposit it in said chamber, and means for operating said fan comprising a shaft extending through one of said standards, a vertical shaft for said blades supported by said base and gearing between the lower ends of said shafts.

11. In a mop-cleaner, the combination of a fan-casing adapted to receive a mop, a base, standards securing the base and casing in spaced relation, means to enclose the space between the casing and base to form a dust collecting chamber, fan-blades for forcing air through the casing to remove the dust from the mop and deposit it in the chamber, and means for driving said fan comprising a shaft extending through one of said standards, gearing between the lower end of said shaft and the fan-blades, and a crank on the upper end of said shaft.

12. In a mop-cleaner, the combination of a base, a fan-casing adapted to receive a mop, fan-blades rotatably mounted in said fan casing for forcing air through the casing to remove the dust from the mop held therein, means for securing the base and casing in spaced relation, means for driving the fan, and a cylindrical chamber between the base and the casing.

13. In a mop cleaner, the combination of a base, a fan casing adapted to receive a mop, fan blades for forcing air through the casing to remove the dust from the mop held therein, means for securing the base and casing in spaced relation, a cylindrical chamber between the base and the casing, and means for driving the fan comprising a vertical shaft for said blades disposed in said chamber.

14. In a mop-cleaner, the combination of a horizontally disposed fan-casing having its upper end formed to receive a mop therein, a dust collector chamber, a horizontally rotating fan mounted in the casing for forcing a current of air through the casing to remove the dust from the mop and deposit it in the chamber, means for driving said fan, and means in the casing to hold the mop fibres so the fan will beat the fibres.

15. In a mop-cleaner, the combination of a horizontally disposed fan-casing having its upper end formed to receive a mop therein, a dust collector chamber, a horizontally rotating fan mounted in the casing for forcing a current of air through the casing to remove the dust from the mop and deposit it in the chamber, means for driving said fan, and means extending horizontally across the fan chamber and adapted to hold the fibres so they will be beaten by the fan blades.

HARRY H. HOOD.
